ENDLESS DIGGER TYPE MINE DREDGER

Jonas L. Roe, Boulder Creek, Calif., assignor to
 Quandro Mining & Equipment Corp., a corpora-
 tion of California

Application November 1, 1947, Serial No. 783,564

5 Claims. (Cl. 37—192)

1

The present invention relates to dredgers. Particularly the invention has for an object the provision of a dredger adapted for tunneling, breasting and general excavation in drift-channel types of mines. The invention eliminates the use of drilling, blasting and manual handling of material under ground.

The invention has for an object the provision of a dredger which is particularly adapted for the mining of minerals. The device functions to remove the ground and to separate the fines or shipping ore from the waste or tailings.

As an example of how a device incorporating the invention may be used, it is customary to first cut into the hill side and form a main tunnel which may have a slight slope. Thereafter cross cuts are made which interconnect the main tunnel. The present invention starts with the end of a cross cut at what is termed the breast. As the dredger operates, ore which is being removed is sorted by the device of the invention, the fines being directed rearwardly of the device for movement outwardly of the main tunnel while the tailings are built up adjacent the breast. In this manner a tunnel is formed and built against the breast at substantially the same time so that the removed cut is refilled. This is known as the retreating method of tunnelling or dredging. It is, of course, understood that the earth prior to tunnelling has been compacted by nature. The tunnelling operation breaks up the earth. However, the refilling is such as to restore the earth substantially to its original condition prior to compacting. In the type of operation performed the device operates upon minerals which are to be mined and a method is followed wherein the gravel is mixed with water as is likewise the tailings. As a rule experience has shown that approximately 35% of the gravel is removed to the surface for processing.

An object of the invention is the provision of a dredger which progressively tunnels the earth formation in a simple and expeditious manner.

A further object is the provision of a dredging machine incorporating a novel form of boom which is operated in a positive manner and whereby the boom may be raised, lowered or turned to the right or left without the use of cables, jib arms, or the like.

A further object is the provision of a dredging machine incorporating a hydraulic means which is positive in its operation and adapted to control operation of a boom.

A further object is the provision in a dredging machine of means which classifies on the job the ore dredged.

2

A further object is the provision in a dredger of a boom having a bucket line adapted to be driven in a positive manner.

Another object is the provision in a dredger of an efficient type of mounting for a boom and which permits the boom to be easily moved.

A further object is the provision of a dredger construction which permits easy assemblage of the various parts, which is efficient in operation and generally superior to dredgers now known to the inventor.

With the above mentioned and other objects in view, the invention consists in the novel and useful provision, formation, construction, association and relative arrangement of parts, members and features, all as shown in one embodiment of the invention in the accompanying drawings, described generally and more particularly pointed out in the claims.

20 In the drawings:

Fig. 1 is a fragmentary side elevation of the dredger of the invention shown in the act of excavating earth;

Fig. 2 is a transverse sectional view on the line 2—2 of Fig. 1, showing the portions of the boom and its operating mechanism;

Fig. 3 is a fragmentary plan view partially in section, schematically showing the hydraulic system for operating the boom, together with an electrical circuit for motors associated with the hydraulic system, the said view being taken substantially on the line 3—3 of Fig. 1;

Fig. 4 is a fragmentary elevation looking substantially in the direction of the arrows on line 4—4 of Fig. 1;

Fig. 5 is a fragmentary sectional view on the line 5—5 of Fig. 7;

Fig. 6 is a fragmentary sectional view on the line 6—6 of Fig. 5;

40 Fig. 7 is a sectional view on the line 7—7 of Fig. 5;

Fig. 8 is an end elevation of the invention looking toward the boom of Fig. 1;

Fig. 9 is a fragmentary view of the dredger in the act of tunneling, and showing movement of certain members thereof in one plane; and,

Fig. 10 is a plan view of the showing in Fig. 9, and illustrating the sweep of an element of the dredger in a transverse direction.

50 Referring now with particularity to the drawings, the dredger 1 includes a tractor 2 mounted on a pair of endless chains 3 and 4, which are ordinarily called "Caterpillars," the chains being driven in any suitable manner for the purpose of propelling the vehicle forwardly or backwardly, together with a boom 5 at one end of the tractor,

which boom includes a bucket line designated generally as 6, the buckets being of the excavating type and which boom, through mechanism designated generally as 7, is capable of being raised or lowered and swung on an arc, together with means 8 adapted to classify or separate certain sized ore from tailings or waste material, all of which means cooperate in the performance of a dredging operation.

While the dredger as an entirety has the appearance shown in Figure 1, still no particular type of tractor or framing is contemplated. It is expected that a framing in a device of the character of this invention should be rigid in structure and adapted to resist stresses of large magnitude. As shown in Figures 5 and 7, the tractor, as to its framing, includes a pair of spaced-apart side walls 9 and 10, a bottom or base wall 11, and a top wall 12, both of which interconnect the side walls. These walls are brazed, welded, or otherwise secured in cooperative relationship.

The framing also includes end walls 13 and 14, the end walls are rigidly secured to top wall 12 in any approved manner, such as by welding. The end walls and side walls 9 and 10 extend above the top wall 12. This provides a space to confine other mechanism utilized in the practice of the invention, as hereinafter detailed.

The means 8, utilized for the purpose of classifying the ore, constitutes a trommel in the form of a perforated drum 15. This drum has annular end members of reduced diameter shown at 16 and 17 which are secured to the main drum structure by annular flanges. The end 16 is passed through an enlarged opening in the end 13 of the framing while end 17 thereof is passed through openings in a pair of members 18 and 19. The arrangement is such that the trommel is supported on rollers at both ends. For instance in Figure 6, a pair of rollers 20 and 21 have trunnions passed between end wall 13 and a wall 22, the rollers being in engagement with the periphery of the reduced diameter member 16 of the trommel. The opposite supporting means for the trommel follows the same practice in that the rollers shown engage the periphery of the reduced end 17 of the trommel. These rollers are interposed between members 18 and 19 and held therebetween by means of trunnions. It is to be observed that end wall 13 is fixed to the frame, whereas members 18 and 19 are removable from said frame so as to permit the trommel to be inserted within the frame and rotatably held therein.

The members 18 and 19 are held separated by an annular spacer piece 23, which spacer piece is provided with a flange 24. The end wall 14 has an enlarged opening 25 and the flange 24 is adapted to be secured by bolts 26 to said end wall. The construction is such that end wall 19 fits within the enlarged opening 25. Thus the walls 18 and 19 are removable as a unit with the opening 25 of such size as to permit ready passage of the trommel therethrough. The trommel is surrounded by a trommel casing 27 of circular form, said casing is welded or otherwise secured to end walls 13 and 22. The opposite end of said trommel casing is fixedly secured to the end wall 14. Thus by providing framing top, bottom and side walls, together with the trommel casing, all secured together in stress-resisting relationship, a rigid frame structure results.

The perforated drum 15 of the trommel externally carries helical blades, blades 28 being

pitched opposite to blades 29 for a purpose hereinafter set forth. The trommel drum is internally provided with a helical blade 30 which is pitched in one direction and extends between the ends thereof. It may be stated that the reduced diameter portion 16 is the inlet end for the trommel and reduced diameter portion 17 is the outlet. The external blades on the trommel are adapted to direct fines to a given location in the trommel casing 27. A motor 31, is positioned on the top wall 12 adjacent the end wall 14. The motor shaft 32 carries a sprocket, not shown. The reduced diameter portion 17 of the trommel drum is provided with a sprocket, not shown, and a continuous chain 33 is passed around the sprockets aforesaid for the purpose of rotating the trommel.

A trough 34 is inclined downwardly within the reduced end 16. This trough is used for feeding ore within the trommel and to assist in said feeding the trough is formed to carry a valved pipe 35 through which water, under high pressure, is directed against any ore received on the trough for reception within the trommel.

Positioned beneath and depending from the base member 11 is a casing 36. This casing is in direct communication with the interior of the trommel casing. The bottom wall 11 and trommel casing 27 have axially aligned openings at 37 and 38 with a wall extending between said members and surrounding the openings. The casing 36 is adapted to house a pair of intermeshing bevel gears 39 and 40, bevel gear 39 being mounted on a shaft 41 suitably journalled in the casing with one end of said shaft carrying an impeller blade 42. Gear 440 is passed through the side wall of the casing and is mounted upon shaft 43 of a motor 44, the motor being external of the casing and secured to the bottom wall 11. The casing 36 is involute in form and has its outlet at 45 (see Figure 1). The outlet is in communication with a flexible hose 46. By way of example, when ore is fed into a rotating trommel, the fines of a given size will pass through the perforations in the trommel and be received upon the inner wall surface of the trommel casing. The helical external blades 28 and 29 will move this material toward the opening which communicates with the casing 36 and the impeller blade will then direct the material so received therein to the outlet of said casing and into the flexible hose. It is obvious that the casing 36 together with the impeller therein and the means for rotating the impeller constitutes one form of sand pump. That material which is received within the trommel and does not pass through the perforations thereof is directed outwardly of the trommel through end 17, being fed by the helical blades 30.

In the practice of the invention, water is used and I provide a pipe 47 which is axially passed through the reduced end portion 17 and into the trommel. The pipe is provided with a series of perforations 48 whereby water may be sprayed on the ore received within the trommel.

The boom 5, with its associated bucket line, is adapted to be moved in various directions so as to perform, in an efficient manner, an earth digging or tunnelling operation. This boom is mounted in a gimbal 49, the gimbal being substantially rectangular in form (see Figure 4), the gimbal having side members 50 and 51 interconnected by top and bottom transverse pieces 52 and 53. The top and bottom transverse pieces are centrally provided with studs 54 and 55 which

are received in bearings carried by top and bottom gimbal supports 56 and 57. The bottom support 57 is secured to the bottom wall 11, while the top support 56 is secured between the end wall 13 and the side walls 9 and 10. As shown in Figure 1, the supports may have offset portions so as to permit the gimbal to readily rotate between said supports.

The boom 5 is mounted in the gimbal 49 at one end thereof. The boom 5 includes a pair of spaced-apart elongated side plates 58 and 59 braced by a longitudinally extending, centrally positioned rib 60, the said rib provided with transverse end pieces 61 and 62, which extend between the side plates. The rib, the transverse pieces, and the side plates are all rigidly secured together. Adjacent the outermost end of the boom, and provided in each side plate, are bearings 63 and 64 adapted to rotatably support therebetween a shaft 65. Positioned between the side plates 58 and 59 and carried by the shaft 65 are sprockets 66 and 67. The opposite end of the boom has the side plates 58 and 59 thereof provided with bearings 68 and 69, carrying a shaft 70. Mounted externally of the side plates 58 and 59 are gears 71 and 72. The sides 50 and 51 of the gimbal are positioned between the side plates of the boom and a gear, as best shown in Figure 4, the gimbal being provided with bearing portions through which the shaft 70 is passed. Sprockets 73 and 74 are mounted on shaft 70, which sprockets are in substantial parallelism with sprockets 66 and 67. Forward of the transverse piece 62 are a pair of axially aligned shafts 75 and 76. These shafts are carried in suitable bearings provided in the side plates 58 and 59; and gears 77 and 78 are carried on ends of said respective shafts, the gear 77 being in mesh with gear 71 while gear 78 is in mesh with gear 72. Carried on the shafts 75 and 76 and within the confines of the side plates 58 and 59 are bevel gears 79 and 80, these bevel gears being in mesh with further independent bevel gears 81 and 82. Bevel gears 81 and 82 are carried on shafts of motors 83 and 84. These motors are mounted in any convenient manner between the rib 60 and the side plates. It will be observed that each motor, when in operation, drives a shaft, which independent shafts 75 and 76 in turn cooperate to drive the single shaft 70. The advantages of this construction will be detailed in the statement of the operation.

Extending between both ends of the boom and over the sprockets 66, 67 and 73, 74 is the bucket line 6. The bucket line includes buckets 85 which are spacedly secured by solid links 86. This bucket line is conventional, and the said links thereof are joined together in the usual manner, such as best illustrated in Figure 2, that is to say, by means of pins passed through knuckles in both the links and the buckets.

The buckets are of the excavating type, which is to say that a sharp tooth or teeth portions 87 are provided for each bucket, which teeth cut the earth formation and deposit the same in the scoop portion of the bucket and hold it therein during travel of the bucket to, in turn, deposit such formation onto the trough 34. No particular form of the bucket is contemplated, as buckets are common in the art.

The mechanism 7 for controlling movement of the boom is detailed in Figure 3. Positioned between the trommel casing 27 and the bottom and side walls of the tractor are elongated cylinders

88 and 89. Each cylinder terminates in end wall 13.

Each cylinder has an intermediate division wall 90 and 91. Each cylinder forward of its division wall, toward the end wall 13, is open-ended while a second portion of the cylinder is closed or provided with a head at 92 and 93. For convenience of description, the open-end portions as applied to each cylinder are designated 10 as 94 and 95 and the closed portions as 96 and 97. Within the closed portions of the cylinders are pistons 98 and 99 and within the open-ended portions of each cylinder are cross-heads 100 and 101. Piston rods designated generally as 102 interconnect the respective cross-heads with a piston and said rods are passed through the division walls 90 and 91 as shown in the figure. Each cross-head has a socket portion 103. Arms 104 and 105 are secured to side plates 58 and 59, each 15 arm at one end carrying a socket 106, 107. Links 108 and 109 are provided with ball ends, as for instance illustrated at 110, which ball ends are positioned between the sockets of the cross-heads and the arms. It is evident that movement of 20 the links will swing the arms 104 and 105 to in turn cause movement of the boom, as hereinafter set forth in the statement of operation.

A hydraulic system is utilized for actuating the pistons in the cylinders, which system is shown 25 diagrammatically in Figure 3. I prefer to use a closed system and accordingly, I provide independent pumps of any type. In the drawing two gear pumps 111 and 112 are provided. A pipe 113 communicates with one end of cylinder portion 96, the opposite end thereof being in communication with pipe 114 leading to either the intake or outlet opening of the gear pump. Pipe 114 connects with a check valve 115, which check valve in turn communicates through pipe 116 30 with a tank 117 and likewise with a check valve 118. Check valve 118 through the medium of pipe 119 connects with the pump at the opposite port thereof, which may be either intake or outlet, and with the opposite end of the cylinder portion 96. Without detailing further, it may be 35 said that the same procedure is followed for the opposite cylinder portion, it being noted that the pump 112 has check valves on opposite sides thereof and that the line 116 communicates with the said check valves. Electric motors 120 and 121 may drive their respective pumps by any 40 suitable means. Each electric motor is in circuit with a reversing switch 122 and 123, the reversing 45 switches leading to overload circuit breakers 124 and 125, the said switches and the said circuit breakers in turn being connected with a source 50 of power supply.

The operation, uses and advantages of the invention are as follows:

55 It is intended primarily that the "Caterpillar" or tread portions 3 and 4 should be positioned beneath the tractor frame rather than in the position shown in Figure 3. This will permit a greater swinging of the boom. To operate the 60 boom in the manner depicted in Figures 10 and 11, the motors 120 and 121 are energized upon the throwing of the reversing switches in one or the other direction, it being intended in the present system that the pumps 111 and 112 should 65 be reversed as to operation and as to the direction in which fluid is passed through the respective pipes. The tank 117 is filled with hydraulic fluid and initially the closed portions 96 and 97 of the cylinders are filled with fluid on both sides 70 of the pistons 98 and 99. To prevent leak, pack- 75

ing is provided in the division walls 90 and 91 at the zone of passage therethrough of the piston rods. The cross-heads in the open-ended cylinder portions 94 and 95 stabilize the thrust on the links 108 and 109 and likewise that on the piston rods 102. If the boom is positioned centrally of the tractor frame, and it is desired to raise the boom from its lowered position of Figure 10 to its upper position as indicated by the dotted line position thereof, hydraulic fluid is pumped behind each piston, that is to say, into the space included between the respective pistons 98 and 99, and the end walls or heads 92 and 93. As fluid fills the space between the pistons and the division walls 90 and 91, it is necessary to bleed this fluid. Hence, assuming proper rotation of each hydraulic pump, the fluid is removed from one side of each piston and directed through the pipes, assuming one side explanation, into pipe 120 through the pump into pipes 114 and 113 rearward of the piston. The other side is operating the same way, with the result that there is a direct thrust upon the piston rods and the associated links which interconnect the arms 104 and 105 and the boom will be moved upwardly, the boom revolving on the shaft 70. To swing the boom transversely or on an arc, as illustrated in Figure 10, one of the reversing switches is thrown, say the switch at 123, whereupon fluid included between the piston 99 and the head 93 is removed or bled and passed to the other side of said piston or between the piston 99 and the wall 91. This is accomplished by reversing the direction of movement of the motor, which reverses the movement of gear pump 112. The operator need not watch the boom movement, as when the boom has swung its full arc, the overload circuit breakers 124 and 125 will operate and break the circuit. In the event that the piston in one or the other of the cylinders does not complete its stroke, one or the other of the one way check valves in the pipes 114 and 119 will open and direct fluid into the line from the tank 117. After sufficient fluid has been obtained the check valves will close. It is evident that when liquid is being removed from one end of the cylinder and directed to the opposite end, that there is a negative pressure on one side of the line and a positive pressure on the other. If this negative pressure is less than atmospheric, a check valve will open and admit liquid from the supply tank. If we assume that the sweep of movement for the boom is at a lower level or in the plane of the solid lines for the said boom, shown in Figure 10, the boom may be held in this position during a sweep by reversing the turning direction of both motors 120 and 121 upon operation of the switches 122 and 123. Liquid is directed behind one of the pistons under pressure, whereas the opposite cylinder removes fluid from behind a piston and directs the fluid under pressure forwardly thereof. This swings the boom. If it is also desired to raise the boom, one or both pistons are moved forwardly to a given position. If a single piston is moved forwardly to a given position, and the other piston retracted, the boom will be brought to a given level and turned, depending upon which piston is actuated. I, therefore, have complete control of boom movement with a device that does not incorporate cables, jibs, or other projecting members, and one that is simpler to operate and more positive in its action.

As illustrated in both Figures 1 and 8, the arms 104 and 105 are curved in part and secured to the side plates of the boom adjacent the low-

ermost edges thereof. This construction affords for leverage so that the device will readily lift the boom as well as swing the same.

The motors 83 and 84 may be of small size and positioned between the rib 60 and a side plate. Thus, the boom is stabilized by this construction and a large single motor is unnecessary. Movement of shaft 70 is controlled by the independent motors which revolve the independent shafts 75 and 76. This construction, in actual practice, gives flexibility to the structure and permits proper movement of the bucket line, particularly when the bucket line is engaging formation which is difficult to cut. The buckets excavate the formation, as shown in Figure 1, and carry the formation along the upper course of the continuous bucket line, the buckets finally depositing the ore onto the trough 34 for reception within the trommel. During movement of the bucket line, the trommel is being rotated by motor 31, motor 44 is energized to revolve the impeller 42, and water is being forced under pressure through line 35 over the trough, while at the same time, water is being passed through pipe 41, through openings 48, and into the trommel. Pipe 41 is eccentric to the axis of the trommel so as not to interfere with ore received therein. I provide a pair of pipes at 126 and 127 which are secured to the trommel casing, as shown in Figure 7, and which pipes have openings communicating with openings in the trommel casing throughout its length. Pipes 126 and 127 communicate with a source of water supply. Thus, as the ore is removed and carried by the bucket line, and dumped onto the trough, water under pressure through line 35 aids in directing such ore within the trommel. The trommel, as it rotates, will feed the ore therein from one end thereof to the other, through the medium of the blades 30, and the fines of a certain size will pass through the perforations of the trommel and be received in the space included between the periphery of the trommel and the inner surface of the trommel casing. The oppositely pitched blades 28 and 29 will feed the material in this space toward the opening which communicates with the casing 36, to be acted on by the impeller 42, and thence directed from said casing 36 rearwardly of the dredger through the flexible hose 46. The tailings of a size not sufficient to allow passage through the perforations are fed outwardly of the trommel through the reduced diameter portion 17, and the flared outlet mouth member 128. Finally, I may protect motor 31 by providing a cover 129, carried by the framing.

I have heretofore detailed in the preamble, a method of removing ore by forming a first cut or main tunnel in the side of a hill, followed by making cross cuts, and then cutting the formation adjacent the breast and by a retreating method, removing the fines and building up the tailings against the breast. The tailings are directed so as to build up against the breast in each case, whereas the fines are directed through the flexible hose 46 for disposition outside the tunnel, the said hose being laid adjacent the main tunnel so that the flow will be outwardly of the hill. In mining operations of the character contemplated for this invention, substantially 35% of the gravel which contains the fines is removed, the remaining percentage largely being tailings or rejects. It is the gravel that is desired as it contains the minerals. For this reason, a sufficient quantity of water is used for mixing with the tailings and the gravel.

The "Caterpillar" or tread portions are operated in the usual manner so that the tractor is at all times moved in accordance with the desires of the operator. The device functions rapidly to cut the formation, to separate the gravel from the tailings or rejects, is of easy operation, and not particularly tiresome to an operator. The operator simply moves switches in one or the other direction to actuate the motors driving the pumps, while other switches control the operation of the bucket line. No particular skill is required, and the operator may stand at one side of the tractor and watch operation while tunneling proceeds.

I claim:

1. A dredger including a tractor frame; a gimbal at one end of said frame; upper and lower gimbal supports secured to the frame whereby the gimbal may rotate on a vertical axis; a shaft mounted on said gimbal transverse to the mounting axis thereof; a boom mounted at one end on said shaft; hydraulic means for swinging the boom vertically on said shaft and transversely upon rotation of the gimbal; said hydraulic means comprising a pair of cylinders, a piston for each cylinder, separate hydraulic pumps, and flow lines leading from said pumps through both ends of the cylinders, the said pistons being connected to the boom.

2. A dredger, including a framing; a gimbal mounted for movement in said framing; a boom mounted for vertical swinging movement in said gimbal, said boom provided with a continuous excavating bucket line; a pair of spaced-apart hydraulic cylinders mounted in said framing, a piston with its arm for each cylinder, links swivelly connected at one end to each piston arm, and at the opposite end swivelly connected to the boom, and means for hydraulically controlling movement of the pistons within said cylinders whereby simultaneous like movement of both pistons in one of two directions vertically swings the boom, and movement of one piston swings the boom transversely.

3. A dredger, including a framing; a gimbal mounted for movement in said framing; a boom having side plates mounted for vertical swinging movement in said gimbal, said boom provided with a continuous excavating bucket line; and hydraulic means for swinging the boom vertically and transversely comprising a pair of cylinders, each cylinder having: a closed end and

- an intermediate wall forming a cylinder head between which wall and the closed end is positioned a piston, that portion of the cylinder outward from the intermediate wall being open ended, a piston arm extending through the intermediate wall, a cross head in the open end of the cylinder, secured to said piston arm; an arm for each side plate of the boom, and separate links swivelly connected at each end between an arm and a cross head, simultaneous movement of the pistons within the cylinder in one of two directions swinging the boom vertically upon the shaft, and movement of one of said pistons in one of two directions turning the gimbal to move the boom transversely.
4. A dredger, including a tractor framing, a gimbal and gimbal supporting means secured to said framing, a boom provided with side plates, a shaft transversely carried by said gimbal and securing one end of said boom, and a pair of motors carried between the side plates of the boom for independently and simultaneously rotating the said shaft.
5. A dredger, including a tractor framing, a gimbal and gimbal supporting means secured to said framing, a boom provided with side plates, a bucket line positioned between the side plates, a shaft carried by said gimbal and securing one end of said boom, a pair of axially aligned shafts carried between the side plates, separate motors for driving each shaft and gearing between each axially aligned shaft and an end of the first-named shaft, and means on said first-named shaft for producing movement of the bucket line when both motors are energized.
